LATCH MECHANISM

Allyn Moore Shaffer and John Burton Hatcher,
Los Angeles, Calif.

Application September 4, 1935, Serial No. 39,109

6 Claims. (Cl. 292—66)

Our invention relates to an improved latch mechanism by means of which a door, window, or hatch, etc., can be closed noiselessly in place of slamming it shut.

5 A further object of our invention is to provide a latch mechanism by means of which a door, window or hatch, etc., may be tightly and securely closed, against either rattling or leakage, by the operation of the latch mechanism 10 itself without the necessity of slamming or otherwise forcing it shut.

Another object of our invention is to provide 15 a latch mechanism by means of which a door may be closed and the latch member engage the latch socket even though the operating means of the latch mechanism is in the position it normally occupies when the latch member is in the extended or closed position.

20 A further object of our invention is to provide a latch mechanism in which the latch member is slidably and swingably moveable, and is slidably moveable independent of the operating means of the latch mechanism.

Another object of our invention is to provide 25 a latch mechanism, the latch member of which in closing is moved sidewardly and outwardly and upon engagement with the latch socket exerts a force thereagainst tending to close said door.

30 Still other objects and advantages of our invention will be made evident hereinafter.

In the accompanying drawing forming part 35 of this application, we have illustrated one preferred form of embodiment of our invention, in which drawing similar reference characters designate corresponding parts and in which:

Figure 1 is a sectional view of the latch mechanism with the door closed.

Figure 2 is a perspective view illustrating one 40 way of connecting the latch member, links and operating arm together.

Figure 3 is a sectional view showing the latch member in a withdrawn position.

Figure 4 is a sectional view showing the position 45 of the latch mechanism as the door is about to be closed by manual operation of the operating means.

Figure 5 is a sectional view showing the position 50 of the latch mechanism when the door is being closed with the operating means of the latch mechanism in the closed position.

Referring to the drawing, a latch member 1, a latch link 2, and operating link 3, a stub arm 4, and an operating arm 5 are located in a horizontal plane between the bearing surfaces 6 and 7

of a door 8. A part of the edge 9 of the door 8 is cut out to allow for the movement of the latch member 1, and part of the edge 9 is bent at right angles and curved as shown in the drawing to provide a guide means 10.

The wall 11 is provided with a wear plate 12 and part of the wall 11 and the wear plate 12 are cut out to provide a latch socket 13, which is adapted to be engaged by the latch member 1.

The outer end of the latch member 1 is curved 10 as shown in the drawing in order to facilitate its movement in and out of the latch socket 13 and for other reasons which will be made evident hereinafter.

Connected to the inner end of the latch member 1 are the outer end of latch link 2 and the upper end of operating link 3. The inner end of latch link 2 is connected to the outer end of stub arm 4. The stub arm 4 is adapted to slide in and out between the flat bearing surfaces 6 and 14, and is held in the outward or normal position by means of a spring or similar mechanism 15, the outward movement of which is limited by means of stops 16.

The lower end of the operating link 3 is connected to the outer end of the operating arm 5 which slides in and out between the bearing surfaces 7 and 17. The connection between the latch member 1, the latch link 2, and the operating link 3, the connection between the latch link 2 and the stub arm 4 and the connection between the operating link 3 and the operating arm 5 may be of any convenient type which in each case allows the free rotation of the connected parts around a common axis perpendicular to the plane of their movement.

The operating arm 5 is held in its outward or normal position as shown in Figure 1 by means of a spring 18, the other end of which is connected to the side 9 of the door 8. The other end of the operating arm 5 is connected to the door levers 19 by means of link 20, bell crank 21 and cross shaft 22.

The latch member 1, the latch link 2, the operating link 3, the stub arm 4, the springs 45 15 and 18, and the operating arm 5 move in a plane parallel to that of the drawing and are so constrained in any convenient manner, as, for example, the flat surface 23 and another flat surface below the plane of the drawing (not 50 shown).

When the door is closed, the latch member 1, latch link 2 and the stub arm 4 are aligned as shown in Figure 1.

In opening the door 8 one of the door levers 55

18 is depressed which moves the operating arm 5 in the direction indicated by the arrow in Figure 3. The operating arm 5 draws the operating link 3 sideward and causes the latch member 1 to be withdrawn sideward and inward at an angle essentially as shown, pivoting around the guide means 10 and disaligning the latch member 1 and the latch link 2. The connection between the latch means 1 and 2 and the operating link 3 moves inward and sideward because of the rotation of the latch link 2 about the outer end of the stub arm 4 (which remains stationary) and the movement of the operating arm 5.

In closing the door one of the door levers 19 is depressed so that the end of the latch member 1 will not engage the wear plate 12. A moderate force is applied to the door in order to partially close it, and when the door is brought into the position shown in Figure 4, the operating lever 19 is released. The operating arm 5 is then moved in the direction shown by the arrow in Figure 4 because of the action of the spring 18 which reverses the previously described motion in opening the door. The outward movement of the operating arm 5 is transmitted through the operating link 3 to the latch member 1, forcing the latch member 1 into the latch socket 13 with a slidably swinging motion, levering against the edge 24 of the latch socket 13. Thus the latch member 1 acts as a lever to exert a considerable force between the edge 24 of the latch socket 13 and the bearing surface 6, thereby levering the door tightly shut against the buffer 25.

As shown in Figure 5, when the door is slammed or pushed shut without depressing one of the door levers 19, the outer end of the latch member 1 engages the wear plate 12, which forces the latch member 1, the latch link 2, and the stub arm 4 substantially as a unit in the direction indicated by the arrow in Figure 5, compressing the spring 15. When the door reaches a position in which the latch member 1 can enter the latch socket 13, the spring 15 forces the stub arm 4, the latch link 2 and the latch member 1 outward, substantially as a unit, forcing the latch member 1 into the latch socket 13, and the entire latch mechanism into the position shown in Figure 1. In the inward motion above described the operating link 3 pivots about the outer end of the operating arm 5 (which remains stationary) thus causing the connection of the latch member 1 and the latch link 2 to be drawn slightly away from the surface 6, but in the subsequent outward motion the connection returns to its previous position. The latch member 1 in returning to its normal position exerts a slight lever action somewhat similar to the lever action exerted in closing the door by the operation of one of the door levers 19, but of course not to the same degree.

In the claims we have used the term latch bolt means to include the latch member 1 and the latch link 2, and the term door to include a door, window, hatch, or similar article.

Although we have described our invention with respect to certain particular embodiments thereof, nevertheless we do not desire to be limited to the particular details shown and described except as clearly specified in the appended claims, since many changes, modifications and substitutions may be made without departing from our invention in its broader aspects, which may be found useful in many other applications thereof.

We claim:

1. In a latching device of the class described the combination of: a latch bolt means including

a pair of toggle members, said latch bolt means being movable into a retracted position by disaligning said toggle members; operating means positively connected to said latch bolt means for moving said toggle members between aligned and disaligned positions, and resilient means yieldingly supporting said latch bolt means and permitting said latch bolt means to be moved into a retracted position by force applied to the end of the bolt means, said operating means causing the toggle members to be slightly disaligned when the latch bolt means is forced into retracted position by the aforesaid application of force and causing the toggle members to be realigned when the latch bolt means is returned to its normal position by said resilient means.

2. In a latching device of the class described the combination of: a latch member in a door, said latch member being one arm of a toggle and simultaneously slidably and swingably movable in a plane to which the jamb edge of said door is substantially normal; and operating means for slidably and swingably moving said latch member in a curved path into a retracted position, said operating means comprising a slidable operating member and a link connecting the operating member to the latch member, said latch member being resiliently supported to permit the retraction of said latch member independently of the retraction of said latch member by said operating means and without moving the slidable operating member.

3. In a latching device of the class described the combination of: a latch member in a door, said latch member being one arm of a toggle and simultaneously slidably and swingably movable in a plane perpendicular to that of the door upon breaking of the toggle; operating means for breaking the toggle for slidably and swingably moving said latch member in a curved path into a retracted position; said latch member being also slidably movable into a retracted position along with the second arm of the toggle independently of the operation of said operating means.

4. In a latching device of the class described the combination of: a latch member simultaneously slidably and swingably movable; operating means for simultaneously slidably and swingably moving said latch member in a curved path into one fully retracted position and in which the major portion of the movement is swinging; said latch member being also slidably and swingably movable into a second fully retracted position and in which the major portion of the movement is sliding.

5. In a latching device of the class described the combination of: a latch member in a door, said latch member being one arm of a toggle, the said toggle being substantially in a straight line when the latch member is in extended position, the other arm of said toggle being yieldingly supported to permit said latch member to be retracted without substantially disaligning said toggle; and means connected to the joint of said toggle for operating said toggle in a plane to which the jamb edge of said door is substantially normal.

6. In a latching device of the class described the combination of: a latch member in a door which is one arm of a toggle and which is movable into a latch socket of the door jamb; a guide means, and operating means for moving said latch member outwardly and pivotably around said guide means, so that the outer part of said latch

member is moved outwardly and sidewardly and upon engagement with the wall of said latch socket exerts a force thereagainst forcing the door shut, said latch member being resiliently supported to permit the retraction of said latch member independently of the retraction of said latch member by said operating means upon

slamming said door shut, said operating means acting automatically during slam shutting of said door to cause a partial pivoting of the latch member around the guide means to exert a force against the latch socket to force the door shut.

ALLYN MOORE SHAFFER.
